UNITED STATES PATENT OFFICE

EDUARD HERZIG, OF WEST HOBOKEN, NEW JERSEY.

SHUTTLE.

No. 811,721.

Specification of Letters Patent.

Patented Feb. 6, 1906.

Application filed June 21, 1905. Serial No. 266,199.

To all whom it may concern:

Be it known that I, EDUARD HERZIG, a citizen of the United States, and a resident of West Hoboken, Hudson county, State of New Jersey, have invented certain new and useful Improvements in Shuttles, of which the following is a specification.

My invention relates to shuttles such as are used in looms; and it consists in the novel construction and arrangement of parts, as will be hereinafter described, the features of novelty being pointed out in the appended claims.

Reference is to be had to the accompanying drawings, in which—

Figure 1 is a face view of a shuttle constructed according to my invention. Fig. 2 is a detail sectional view of the spool-support, and Fig. 3 is an elevation thereof.

A is the body of the shuttle, provided with the usual rack B and having a recess or chamber C. A second recess or chamber D is arranged within the chamber C and contains two pivoted spring-arms E' and F, provided with eyelets E' and F' and constituting a tension device. This part of the shuttle may be of any ordinary construction and forms no part of the present invention. A hollow support or rod G extends upwardly from the bottom C' of the chamber C and is provided with a sleeve H, which in the present instance is somewhat shorter than the rod G. A coil-spring I is arranged around this sleeve and has its one end secured thereto at J and its other end fastened at K, the coils of said spring I becoming wider apart as they near the free end of the sleeve H. The object of this construction will become apparent from the description hereinafter. A spool L is provided with a pin M and carries the thread N, which passes from the spool L down through the rod G, through the eyelets E' and F' of the spring-arm E and F, and through eyelets O and an opening P out of the shuttle. An arm Q, pivoted at R, is arranged to swing across the free end of the rod G, the free end of said arm Q entering a notch S in the body of this shuttle when said arm is in position over the support G. In operation the spool L is placed on the support G, the pin M engaging the upper coil of the spring L. The said spool is then turned, the coils of the springs acting as a screw-thread, serving to lock the pin M and

with it the spool in position on the support. 55 The end of the spool does not engage the bottom C' of the chamber C when the spool is in position on the support, thus doing away with any friction between the end of the spool and the bottom of the chamber during 60 any rotation of the spool which might take place as a pull is exerted on the thread from any cause. It is to be understood that the thread leaves the spool in the same direction in which the spool is turned in locking it to 65 the support, so that any pull on the thread will fasten the spool on the support more securely, it being understood that the spool L does not turn as the thread leaves it. The arm Q serves as an additional means to prevent the spool from leaving the support. 70

With my device I obtain a simple and efficient device for securing the spool in position in the shuttle, which locking device is flexible or resilient, and thus also serves as a device for equalizing the tension on the thread during the operation of weaving. By having the coils of the spring wider apart as they near the free end of the sleeve H a quick locking of the spool with the support is secured, the coils of the spring acting as a steep screw-thread. 75

Various modifications may be made without departing from the nature of my invention. 80

I claim and desire to secure by Letters Patent—

1. In a shuttle, a support, a coil-spring arranged around said support, and a spool adapted to be carried by said support and provided with a pin arranged to engage said coil-spring to lock the spool to the support. 90

2. In a shuttle, a support, a spool adapted to be carried by said support, and a resilient member for locking said spool to the support. 95

3. In a shuttle, a support, a spool adapted to be carried by said support, and provided with locking means, and a coil-spring engaging said locking means for locking said spool to the support. 100

4. In a shuttle, a support, a sleeve on said support, a coil-spring around said sleeve, a spool adapted to be carried by said support, and a projection on said spool arranged to engage said coil-spring to lock the spool to the support. 105

5. In a shuttle, a support, a coil-spring around said support, the coils of said spring

becoming wider apart as they near the free end of the support, a spool, arranged to be slipped over the free end of said support and provided with a projection adapted to enter into engagement with the coil-spring at the point where the coils are widest apart, to lock the spool to the support.

In testimony whereof I have signed this specification in the presence of two subscribing witnesses.

EDUARD HERZIG.
